DESIGN FOR A WINDOW GREENHOUSE

Clement G. Ewertz, Scotch Plains, N. J., and
Thomas Edward King, Hartsdale, N. Y.

Application December 29, 1939, Serial No. 89,198

Term of patent 14 years

To all whom it may concern:

Be it known that we, Clement G. Ewertz and Thomas Edward King, both citizens of the United States and residents, respectively, of Scotch Plains, in the county of Union and State of New Jersey, and of Hartsdale, in the county of Westchester and State of New York, have invented a new, original and ornamental Design for a Window Greenhouse, of which the following is a specification, reference being had to the accompanying drawing, forming part thereof, in which

Fig. 1 is a perspective view of a window greenhouse showing our new design;

Fig. 2 is an edge view of the window greenhouse shown in Fig. 1; and

Fig. 3 is a top plan view of the window greenhouse shown in Fig. 1.

We claim:

The ornamental design for a window greenhouse, substantially as shown.

CLEMENT G. EWERTZ.

T. EDWARD KING.
